UNITED STATES PATENT OFFICE

167,078

INFLATABLE WATER TOY

Elliott Harrowe, Hollis, N. Y.

Application March 9, 1951, Serial No. 14,440

Term of patent 3½ years

(Cl. D34—15)

To all whom it may concern:

Be it known that I, Elliott Harrowe, a citizen of the United States of America, residing at Hollis in the county of Queens and State of New York, have invented a new, original, and ornamental Design for an Inflatable Water Toy, of which the following is a specification, reference being had to the accompanying drawing, forming part thereof.

In the drawing the figure is a perspective view of an inflatable water toy, showing my new design.

The back of the water toy is identical with the front shown in the said figure.

I claim:

The ornamental design for an inflatable water toy, substantially as shown and described.

ELLIOTT HARROWE.
